UNITED STATES PATENT OFFICE.

EDWIN HART, OF ROCHESTER, NEW YORK, ASSIGNOR TO BAUSCH & LOMB OPTICAL COMPANY, OF ROCHESTER, NEW YORK, A CORPORATION OF NEW YORK.

LENS-SURFACING MACHINE.

Application filed October 2, 1920. Serial No. 414,230.

My present invention relates to grinding machinery and more particularly to machines for forming lenses and it has for its object to provide a simple, durable and efficient machine of compact proportions for surfacing lenses the improvements being directed in part toward providing means for diversifying to a high degree the path of the lens block or the relative movement of the lens and the abrading or polishing surface with which it is in contact. A further object of the invention is to provide an attachment for controlling the movements of the lens block during work on toric lenses and to these and other ends the invention resides in certain improvements and combinations of parts all as will be hereinafter more fully described the novel features being pointed out in the claims at the end of the specification.

In the drawings:

Figure 1 is a side view of a lens surfacing machine constructed in accordance with and illustrating one embodiment of my invention;

Figure 2 is a front view thereof;

Figure 3 is a rear view;

Figure 4 is a top view;

Figure 5 is a fragmentary section on the lines 5-5 and 5^x-5^x of Figure 4;

Figure 6 is a vertical central section taken in a plane extending from front to rear of the machine;

Figure 7 is a central vertical section with parts broken away, taken in a plane extending transversely of the machine;

Figure 8 is an enlarged horizontal section through the frame showing in plan view the mechanism below the spindle;

Figure 9 is an enlarged section on the line 9-9 of Figure 6;

Figure 10 is a similar section on the same line but showing the parts in another position;

Figure 11 is a section on the line 11-11 of Figure 6, and

Figure 12 is a section on the line 12-12 of Figure 6.

Similar reference numerals throughout the several views indicate the same parts.

The machine of the present embodiment of the invention is designed for use as a surfacing and polishing machine and comprises a frame 1 having a hollow base or bed 2 and, above the latter, a head 3 in the form

of a gear case. Referring first to the lower mechanism associated with the bed 2, there is mounted within the latter in cone bearings 4 formed by set screws 5 a rock shaft 6 provided centrally with an enlargement 7 in 60 which is mounted a tapered post 8. These parts extend upwardly through an opening 9 in the base and the post 8 carries the cast iron or other detachable grinding shell 10 having the grinding face 11 of proper curvature to which the rouge or abrasive is applied to surface the lens according to well known principles or the shell surface is covered with felt or flannel for polishing purposes. Beneath the shell on the enlargement 70 7 an annular tray 12 conceals the opening 9 and catches the drippings from the shell, thus protecting the moving parts below. A rigid arm 13 shown in full lines in Figure 7 and in dotted lines in Figure 1, extends rearwardly from the rock shaft 6 and is provided with a wrist pin bearing 14 and pin 15 connecting the arm to a vertically disposed eccentric rod 16 whereby the rock shaft 6 is operated to slowly oscillate the shell 10 in a 75 front to rear direction for purposes herein-after explained. A strap 17 at the upper end of the rod 16 (Figure 5) embraces an eccentric 18 on the main driving shaft 19 of the machine which shaft extends transversely through the head 3. It is fitted with a driving pulley 20 enclosing clutch mechanism and reducing mechanism for the eccentric (the latter being indirectly mounted on the shaft through the medium of a 80 sleeve 21, Figure 5) controlled by exterior knurled operating elements 22 and 23 but these details need not be further explained as they form no part of the present invention.

The lens block or holder and the one in the present instance, which carries the work-piece or lens L is the usual button 24 to which the lens is cemented and it is driven by mechanism suspended from the head 3. In the under side of the latter is a vertical bearing 25 alined with the post 8 of the lower mechanism and turning in this bearing is a sleeve 26. A worm gear 27 integral with the sleeve or fixed thereon takes the thrust against the upper end 28 of the bearing while a cap nut 29 engages correspondingly at the lower end (Figure 6). A worm 30 extending transversely through the head 3 drives the sleeve relatively slowly 105 110

through the medium of the gear 27 and the worm as shown in Figure 7, is driven from the main shaft 19 through gears 31 and 32.

Extending eccentrically through the sleeve 26 and having its bearing therein is a spindle 33 that is also capable of being reciprocated longitudinally for which purpose its driving connections include a key way 34 formed therein and slidably engaged by a key 35 regulated by a set screw 36 in a disc 37 surrounding the upper end of the spindle and resting upon the upper end of the sleeve 26. A packed cap plate 38 overlying the disc beneath an opening 39 in the cover 40 of the head 3 through which the spindle extends protects these and other bearing surfaces from dust and dirt. Rotatably mounted on the sleeve 26 below the disc 37 and held in place by a collar 41 is a spiral gear 42 meshing with a spiral gear 43 on the main driving shaft 19. An upwardly extending pin 44 on the gear 42 takes into a radial slot 45 in the disc 37 containing the key 35 and the spindle 33 is thus driven by the disc from the gearing 42-43, the slot and pin connection taking care of the revolving movement of the spindle due to its eccentricity in the driven sleeve 26 that is otherwise rotated as before described. There is thus given to the spindle both a rotating and a revolving motion.

At its lower end the spindle carries a radially extending slotted dog 46, the spindle being bifurcated for the purpose and the dog being secured in the desired position by a bolt 47. Above it is an annular tray 48 pinned to the spindle at 49 to catch impurities that might otherwise drop upon the grinding surface from the bearings in the head. An offset finger 50 on the dog 46 engages in a socket member 51 having a ball and socket connection shown at 52 with the button 24 on which the lens L is carried. The dog 46 is adjusted to take care of buttons and shells of different sizes used for grinding lenses of different sizes.

It will be seen from the foregoing that the spindle 33 rotates at a relatively high speed while undergoing a revolving movement due to the lower speed of rotation of the sleeve 26 in which it is eccentrically carried, so that the path of the lens on the finishing or polishing shell 10 is much diversified, giving a uniform grinding or polishing action, but in addition to this and to prevent waves in the polished surface beyond any possibility, I provide the slow rocking motion from the eccentric rod 16 for the shell 10.

The grinding pressure and that for holding the dog 46 in the socket member of the button is provided by a lever 53 mounted on top of the head 3 and turning on a shaft 54 which itself is capable of turning in bearings arranged in brackets 55 on the head cover 40. The lever is connected to the

spindle 33 by links 56, the lower ends of which are pivoted to a cross head 57 slideable transversely on the spindle beneath a cap 58 (Figure 2) to compensate for the eccentric motion of the spindle. By this means the spindle may be lifted to disengage the dog 46 for inspecting the work or to change or interchange the grinding parts. Downward pressure is communicated to the spindle in the reverse direction by a finger 59 on the under side of the lever 53 that bears upon the cap 58 at the upper end of the spindle. The normal grinding pressure is maintained by a spring best shown in Figures 4 and 6 having an intermediate loop 60 bearing upon the lever 53 and its end portions wound about the shaft 54 and secured thereto by pins 61. Thus, rotating the shaft 54 increases or decreases the tension of the spring and hence the pressure and this rotation is effected by a worm gear 62 driven by a worm 63 on a hand operated shaft 64 having a bearing at 65 and provided with a knurled thumb-piece.

In the present instance, I have shown the socket member 51 carried by and threaded in the arm 67 of what I term a "toric" attachment by means of which the button is guided in the two planes of curvature of a toric lens. The said arm is bifurcated, as shown at 68, and carries a wrist pin 69 by means of which it is mounted in a bearing 70 adjustably mounted for height on a rod 71 by means of a set screw 72. The lower end of the rod 71 is bifurcated at 73 to carry a wrist pin 74 having a bearing in a member 75 permitting the rod to rock laterally of the machine. The bearing 75 is itself carried by a relatively transverse rock shaft 76 extending transversely of the machine and supported in cone bearings provided by set screws 77 in the sides of the base 2, as clearly shown in Figure 3 and this provides for a movement in a front to rear direction. In other words, the arm 67 has a universal movement and may rock forwardly and rearwardly on one curve and transversely on the other.

A machine constructed in accordance with my invention is simple and compact, convenient to operate and adjust and gives highly uniform results on the grinding surface.

I claim as my invention:

1. In a lens surfacing machine, the combination with a non-rotatable grinding shell, of a lens block cooperating therewith, means for imparting a planetary movement thereto upon the surface of the shell and means for pivotally oscillating the shell relatively to the orbital path of the lens block.

2. In a lens surfacing machine, the combination with a grinding shell and a rotary lens block cooperating therewith, means for imparting a planetary movement thereto on the surface of the shell, of means for re-

peatedly oscillating the shell about an axis in a direction transverse to the axis of the lens block.

3. In a lens surfacing machine, the combination with a grinding shell, of a rotary lens block cooperating therewith, means for rotating and revolving the lens block on the surface of the shell, and means for pivotally oscillating the shell.

10 4. In a lens surfacing machine, the combination with a frame, a grinding shell pivotally mounted thereon for oscillating movement, and means for oscillating the same, of a lens block cooperating with the shell, a sleeve 15 having bearings in the frame, means for rotating the sleeve, a shaft eccentrically mounted in the sleeve and adapted to rotate the lens block and means for driving the shaft.

5. In a lens surfacing machine, the combination with a frame, a rotary sleeve having

bearings therein and a rotary shaft eccentrically mounted in the sleeve, of a rock shaft, means for driving the same, a grinding shell carried on the rock shaft and a lens block driven by the rotary shaft and 25 cooperating with the shell.

6. In a lens surfacing machine, the combination with a frame, a grinding shell mounted thereon, a lens block cooperating with the shell and a reciprocatory and rotary shaft 30 in the frame for driving the lens block, of an arm operatively connected to the shaft to reciprocate the same and to press the lens block against the shell, a rock shaft for said arm, a spring secured to the rock shaft and 35 bearing against the arm and means for adjustably rotating the rock shaft to change the tension of the spring.

EDWIN HART.
